Primary Examiner — Antoine D Davis(74) *Attorney, Agent, or Firm* — Lathrop & Gage LLP**CLAIM**

The ornamental design for a base of a multi-parameter sonde, as shown and described.

DESCRIPTION

FIG. 1 is a top, front, side perspective view of a base for a multi-parameter sonde;

FIG. 2 is a side view thereof, it being understood the other side is identical in that the surface shape is cylindrical; and, FIG. 3 is a bottom view thereof.

The broken line showing of structural features is included for the purpose of illustrating non-claimed subject matter and forms no part of the claimed design.
